UNITED STATES PATENT OFFICE.

JOHN H. SIDDALL, OF CANTON, OHIO.

DENTAL-DRILL HAND-PIECE.

SPECIFICATION forming part of Letters Patent No. 296,078, dated April 1, 1884.

Application filed July 28, 1883. (No model.)

To all whom it may concern:

Be it known that I, JOHN H. SIDDALL, a citizen of the United States, residing at Canton, in the county of Stark and State of Ohio, have invented certain new and useful Improvements in Dental Drills, of which the following is a specification, reference being had therein to the accompanying drawings.

Figure 1 is a side view of my improved hand-piece or holder for dental drill. Fig. 2 is a top view of the same. Fig. 3 is a horizontal section through the part which supports the guide-pulleys. Fig. 4 is a top view of a modified form of drill.

A represents the non-rotating barrel or shell within which the drill-stock and drill are supported. The stock or stem of the drill extends somewhat behind the end of the aforesaid shell or barrel A, and the rearwardly extending part carries a belt-pulley, B, and a heavy wheel, B', which serves as a hand-wheel, and also as a fly-wheel and counterbalance to keep the implement in a horizontal position when desired. At one end of the barrel or shell A there is a plate, C, which projects upwardly, and is cast with or secured rigidly to the said barrel. The drill is revolved by means of a belt, E, which passes around the pulley portion B. The belt extends upward and passes over a pulley carried by a spring, and from there runs to the engine, these latter devices not being shown; or, in place of these, any other suitable means of suspension may be employed. In order to guide properly that portion of the belt which is in immediate proximity to the pulley portion B, I employ a two-part holder, the parts of which are separable, when it is desired to put in place the belt or remove it. As the belt-holders have been heretofore constructed, an inferior support was provided, and the means which were intended to hold the belt in place have not efficiently attained that end, and serious disadvantages have resulted from their use. The holder which I provide for the belt firmly holds it in proper position relatively to the pulleys, and prevents its escape therefrom under any circumstances.

H is a plate or block formed integrally with or secured to the plate or bar C. In the inner face of this block are formed slots or recesses h, one upon each side thereof.

H' is the other part of the guide, it having also recesses or slots h' in its inner face corre-

sponding to the recesses h in the opposite block. These recesses may be only large enough to freely allow the belt to pass up or down through them, as shown in Figs. 3 and 4, or they may be long enough to support anti-friction pulleys or rollers G G', the pulleys G being mounted in the block or bar H by means of bearing-screws h' h', and the pulleys G' being mounted in the part H' by screws h'.

When the two parts of the guide are clamped together, the pulleys are brought sufficiently close together to properly encircle the belt or cord passing to and from the pulley B.

I I are clamping screws or bolts by which part H' can be fastened against the part H.

When it is desired to insert the belt in place, the block or bar H' is withdrawn, the belt is placed around the pulley B, and then the block or bar is put again in position, each strand of the belt lying between the pulleys G G' on one side, and afterward the bolts or screws I I are turned up, thereby clamping tightly together the two blocks or bars H H'. The arms i keep the belt in position in such manner as to entirely prevent its escape when the device is in operation. The spring-fastenings which have been heretofore used have been very troublesome in this respect, they permitting the belt to fly off from the pulley when moving at a high speed.

What I claim is—

85

1. In a hand-piece for chucks or drill-holders for dental engines, the combination, with the revolving drill provided with a pulley or belt-holder, of a belt-guide formed in two parts, each having jaws arranged oppositely to those on the other, the parts carrying the jaws being separable from each other, and means for clamping them together, substantially as set forth.

2. In a drill-holder for dental engines, the combination of the revolving drill-holder, the pulley B, the stationary pulley-support H, having the pulleys G G', and the pulley-support H', adapted to be withdrawn from and to be forced up against the pulley-holder H, too to clamp the belt in place between the pulleys, substantially as set forth.

In testimony whereof I affix my signature in presence of two witnesses.

JOHN H. SIDDALL.
